UNITED STATES PATENT OFFICE

138,804

DESIGN FOR A TOY HELICOPTER OR SIMILAR ARTICLE

Arthur P. Swanson, Chicago, Ill.

Application June 24, 1944, Serial No. 114,187

Term of patent 14 years

(Cl. D34—15)

To all whom it may concern:

Be it known that I, Arthur P. Swanson, a citizen of the United States and a resident of the city of Chicago, in the county of Cook and State of Illinois, have invented a new, original, and ornamental Design for a Toy Helicopter or Similar Article, of which the following is a specification, reference being had to the accompanying drawing forming a part thereof.

On the drawing, the figure is a perspective view of the toy helicopter, or similar article, showing my new design.

I claim:

The ornamental design for a toy helicopter or similar article, as shown.

ARTHUR P. SWANSON.
